UNITED STATES PATENT OFFICE.

HARRY H. HOOD, OF CHICAGO, ILLINOIS, ASSIGNOR TO SPRAGUE CANNING MACHINERY COMPANY, OF CHICAGO, ILLINOIS, A CORPORATION OF ILLINOIS.

METHOD OF PACKING CANS.

1,071,051.

Specification of Letters Patent. Patented Aug. 26, 1913.

Application filed January 5, 1912. Serial No. 669,702.

To all whom it may concern:

Be it known that I, HARRY H. Hood, a citizen of the United States, residing at Chicago, in the county of Cook and State of Illinois, have invented certain new and useful Improvements in Methods of Packing Cans, of which the following is a specification.

My invention relates to improvements in methods of packing cans, and refers particularly (although not exclusively) to the packing of food products in cans which are to be subsequently closed by the application of a cap which is soldered in place.

My invention is especially adapted for use in the case of a can having a top which contains an aperture therein of less diameter or size than that of the cross-section of the can. According to the construction of can which is ordinarily employed, the receiving aperture through which the meat, vegetable, food or other product is introduced is provided around its periphery with a groove or crease adapted to receive the downturned edge of the cap which effects the closure. It has been found that particularly in packing meats and other solid material a portion of the latter is likely to protrude from the can and extend into or foul the above-mentioned groove in the can top so that it becomes difficult to solder the cap in position. A considerable amount of additional labor is required in order to clean or remove the material from this groove before the soldering can be satisfactorily accomplished.

It is the object of my invention to improve the method of packing so that the material will be prevented from coming in contact with this groove, whereby there may be no delay in applying the caps and soldering them in position.

I accomplish the desired results by providing a packing tube which registers with the receiving aperture of the can. The meat or other material to be packed is placed within this tube, and on top of the material is placed a protector, shield, or retainer constructed of pasteboard, metal or other suitable substance which possesses a slight amount of resiliency. This retainer when first placed in position overlaps, in certain portions at least, the bore of the tube. A plunger is brought into contact with this retainer and forces it and the food into the can, the portions of the retainer which over-

lap the tube being folded against the sides of the end of the plunger, this end being preferably of less diameter than the main body of the plunger for the accommodation of these folded portions. When the contracted retainer reaches the lower end of the tube, the folded edges are released and become partially flattened, whereby the retainer (now inside of the can) overlaps the receiving aperture of the can top and prevents the packed material from protruding from the can and coming in contact with and fouling the groove or crease in the can top. These and other advantages of my invention will be more readily understood by reference to the accompanying drawings, which show a preferred embodiment of means for carrying out my improved process, and in which—

Figure 1 is a diagrammatic vertical section through a packing machine; Fig. 2 is a perspective of one form of retainer; Fig. 3 is a perspective of a modified form of retainer; Fig. 4 is a perspective of a second modified form of retainer; and, Fig. 5 is a fragmentary vertical section through a portion of the can, showing the retainer and can cap in place.

The packing machine consists of a base 10 having integral therewith a supporting bracket 11. The base 10 also has the platform 12, on which the can 13 may be placed. Vertically movable within the bearing 14 of the bracket 11 is the plunger 15, which is actuated by any suitable mechanism, and which, for the sake of simplicity, has not been shown. The lower end 16 of the plunger is preferably of slightly smaller diameter than the main portion of the latter, for the purpose which will be explained hereafter.

Vertically movable within the bearing 17 of the bracket 11 is a packing sleeve 18, the upper end of which is preferably provided with a flange 19. The inner diameter of the packing sleeve 18 is preferably substantially the same as the outer diameter of the main portion of the plunger 15, so that as the latter passes through the packing sleeve it has a snug fit therein. The upper end of the packing sleeve 18 is adapted to receive the retainer or protector 20, which is of pasteboard, metal or other suitable material.

The can 13 which is packed by means of

my apparatus is of the well-known type, and has a top 21 in which is the receiving aperture 22. Around the periphery of this aperture the top 21 is formed with a V-shaped groove 23.

Having thus described the apparatus which I employ, the method of operation may now be readily understood: The can 13 being placed in position on the platform 12, the packing tube 18 is brought into register with the receiving aperture 22. A desired amount of meat or other material to be packed is then placed within the tube 18 and the retainer 20 is placed on the upper end of the tube. The plunger 15 is now actuated, and its end 16 first comes in contact with the retainer 20. On account of the fact that the latter overlaps the tube 18, the edges of the retainer are folded upwardly around the end 16 of the plunger, this condition of the retainer being indicated in dotted lines in Fig. 1. As the plunger 15 moves downwardly the meat or other material 24 within the tube 18 is forced into the can 13 and the retainer is forced through the tube in contracted condition. After the retainer 20 has been carried down into the can so that its upturned edge 25 is disengaged from the lower end of the packing tube 18, this edge straightens out and the retainer assumes the position within the can indicated in Fig. 1, thereby preventing the material 24 within the can from coming in contact with the groove 23 in the can top. The plunger 15 is now moved upwardly and the tube 18 is slightly raised in order to allow the can 13 to be removed. A new can is then placed in position and the same operation is repeated.

The tube 18 may be made of such dimensions that it is of a size to exactly contain a sufficient amount of material to fill the can and thus may act as a measuring device; or it may be of smaller capacity than the can, in which case the retainer is applied only when the final charge of meat or other material is packed.

The retainer which I preferably employ is circular and constructed of pasteboard, its shape being shown in Fig. 2. If desired, however, an aperture 26 may be used in the retainer, thereby more readily allowing the escape of air through the vent of the cap when the meat or other material is subsequently heated. A retainer having such an aperture is indicated in Fig. 3.

In Fig. 4 I have shown a still further modified form of retainer 27 which may be constructed of metal and in which only the ends 28 are folded upwardly as the retainer passes through the tube 18. I have found that in many cases it is satisfactory to employ a retainer of this type to keep the material from coming in contact with the groove 23 in the can top.

After the can 13 has been packed and the retainer is placed in position, the can cap 29, of the usual type, is applied and soldered in place. This cap is provided with the vent 30, which is tipped in the well known manner in order to effect the final closure.

It will be apparent to those skilled in the art that many changes could be made in the improvements which I have described without departing from the spirit or scope of my invention.

What I claim is:

1. The method of packing material in a receptacle having an apertured wall, which consists in introducing said material into said receptacle through said aperture, and inserting a retainer in contracted condition through said aperture, whereby after its introduction into the receptacle said protector on expansion will act to prevent the contents of said receptacle from protruding from the latter and fouling the outer portion of said wall, thereby facilitating the application and sealing of a cap for closing said aperture, substantially as described.

2. The method of packing material in a receptacle having an apertured wall, which consists in simultaneously forcing said material and a retainer through said aperture into said receptacle, said retainer adapted to extend beyond the margin of said aperture, thereby retaining the contents in the receptacle and preventing their coming in contact with the outer surface of said wall, substantially as described.

3. The method of packing material in a receptacle having an apertured wall, which consists in simultaneously forcing said material and a retainer in contracted condition through said aperture into said receptacle, thereby causing said retainer to extend beyond the margin of said aperture when the retainer expands after its passage through the aperture, whereby the contents of the receptacle will be prevented from coming in contact with the outer surface of said wall and fouling the latter, substantially as described.

4. The method of packing material in a can having an apertured top, which consists in introducing the material into a packing tube, placing a retainer on top of said material, said retainer overlapping said tube, and simultaneously forcing said material and said retainer through said tube into said receptacle, whereby the retainer will pass through said aperture in contracted condition, thereby preventing said material from coming in contact with the outer surface of said top when the retainer subsequently expands within the can, substantially as described.

5. The method of packing material in a can having an apertured top, which consists in placing the material in a packing tube in

register with said aperture, placing a retainer on the end of said tube, and forcing a plunger through said tube, thereby carrying said material and said retainer through said tube and into said receptacle, the edge of said retainer being folded against the end of said plunger during its passage through the tube, said folded portion subsequently ex-

panding within the receptacle, whereby the contents of the latter are prevented from 10 coming in contact with the outer surface of said top, substantially as described.
